UNITED STATES PATENT OFFICE.

HERMAN M. HOELSCHER, OF CHICAGO, ILLINOIS, ASSIGNOR TO L. WOLFF MANUFACTURING COMPANY, OF CHICAGO, ILLINOIS, A CORPORATION OF ILLINOIS.

DESIGN FOR A VALVE-SHELL FOR STOP-COCKS.

No. 39,551.

Specification for Design.

Patented Sept. 15, 1908.

Application filed April 10, 1903. Serial No. 152,182. Term of patent 14 years.

To all whom it may concern:

Be it known that I, HERMAN M. HOELSCHER, a citizen of the United States, residing in Chicago, in the county of Cook and State of Illinois, have invented a new, original, and ornamental Design for Valve-Shells for Stop-Cocks, of which the following is a specification.

The accompanying drawing is a side view

of the valve shell for stop cock showing my design.

I claim—

The ornamental design for a valve shell for a stop cock, as shown.

HERMAN M. HOELSCHER.
